CLAIM

The ornamental design for a food container lid, as shown and described.

DESCRIPTION

FIG. 1 is a top, front, left perspective view of a food container lid, showing the new, original and ornamental design;

FIG. 2 is a front elevation view thereof;

FIG. 3 is a left side elevation view thereof;

FIG. 4 is a rear elevation view thereof;

FIG. 5 is a right side elevation view thereof;

FIG. 6 is a top plan view thereof;

FIG. 7 is a bottom plan view thereof; and,

FIG. 8 is a top, front, left perspective view of the food container lid of FIG. 1, shown in condition of use.

The food container lid is shown with two symbolic breaks on the locking tabs. The appearance of any portion of the article between the break lines forms no part of the claimed design. The broken lines in the drawings depict portions of the food container lid that form no part of the claimed design. The

(Continued)

broken lines showing a food container in FIG. 8 depict environmental subject matter that form no part of the claimed design.
